UNITED STATES PATENT OFFICE.

ARCHIE D. PEPIN AND FRANK P. W. HAACK, OF BEND, OREGON.

TOY PISTOL.

Application filed November 13, 1924. Serial No. 749,702.

This invention relates to new and useful improvements in pistols, and particularly to toy pistols to be used in killing flies.

One object of the invention is to provide a device of this character which is simple in construction, and which is easy to operate.

Another object is to provide a device of this character which includes a rubber band as the missile, and wherein a portion of the trigger mechanism is arranged to produce a whirring or whistling sound each time the pistol is discharged.

Other objects and advantages will be apparent from the following description when taken in connection with the accompanying drawing.

In the drawing:

Figure 1 is a side elevation of a pistol made in accordance with the present invention, and in position to be discharged.

Figure 2 is a top plan view of the pistol.

Figure 3 is an enlarged vertical longitudinal sectional view on the line 3-3 of Figure 2.

Referring particularly to the accompanying drawing, there is shown a pistol body including the hand-grip 10, and the barrel portion 11. Formed vertically through the rear end of the barrel portion is an opening 12, and in the lower portion of the rear wall of this opening there is formed a projection 13, against which the rear face of the upper end of the trigger 14 is arranged to bear, and which serves as a stop to limit the movement of the trigger. The trigger is mounted on the transverse pin 15. In the upper portion of the opening 12 there is disposed a rotary member 16, which is supported on the transverse pivot pin 17, and which has the plurality of radial arms 18, each of which is adapted to project above the upper end of the opening, when the member is rotated.

The forward face of the upper end of the trigger is provided with a flat portion which is arranged to engage with the rear face of the free end of one of the arms 18, while the rear face of the upper end of the trigger bears against the before-mentioned projection 13, whereby to resist any effort to rotate the member 16 forwardly.

A rubber band is placed with one end transversely in a recess 19, formed in the forward end of the barrel 11, and the other end looped around the upwardly projecting arm 18 of the member 16. Upon grasping

the trigger and pulling same rearwardly toward the hand grip 10, the member 16 will be given a slight rearward rotation sufficient to permit the upper end of the trigger to pass forwardly of the arm engaged therewith. The trigger is thus released from the member 16, when the rubber band will shoot forwardly off the end of the barrel, and strike a fly at which the pistol was aimed. The forward movement of the rubber band causes the rapid rotation of the member 13, which will continue for a brief period.

The free end of each of the arms 18 is formed with an opening 20, and as the member 16 rapidly rotates, the air passing across these openings will produce a whirring or whistling sound.

It will be noted that the trigger depends vertically by gravity, and upon drawing the rubber band backwardly and engaging or looping same over the upwardly extending arm 18, the member 16 will be rotated sufficiently to engage its diametrically opposite, and downwardly directed arm 18 against the trigger, which forces the trigger against the projection 13. The pistol is thus cocked, when the user points the same at a fly, or other object, and pulls the trigger, to permit the rubber band to shoot from the barrel, and cause the member 16 to rotate and produce its sound.

What is claimed is:

1. A toy pistol including a barrel and hand-grip, a trigger, a flexible missile, and a rotatable detent for engagement with the missile and with the trigger, said detent being arranged to rotate rapidly when released from the trigger and having openings against which air impinges to produce sounds.

2. A toy pistol including a pistol body, a trigger mounted in the body, a rotatable detent mounted for engagement with the trigger, means on the body for engagement by the trigger to hold the rotatable detent against rotation, said detent being formed with peripheral openings across which air passes to produce whistling sounds, and an elastic band releasably engaged with the body of the pistol and said detent.

3. A toy pistol including a body having an opening therethrough, one wall of the opening having a projection, a trigger pivotally supported in the opening and arranged to bear against the projection, a detent rotatably mounted in the opening above the

trigger and having radial arms each of which is arranged to successively engage the trigger and another arm project above said opening, and an elastic band arranged to be engaged around the end of the body and said projecting arm.

4. A toy pistol of the character described, comprising a handle grip and barrel having a recessed portion provided in the top 10 and adjacent the rear end thereof, a rotary disk arranged within the recess portion and including oppositely extending hammer heads upon its periphery, a trigger pivotally mounted within the lower portion of the 15 recess portion and having its upper end engaged in the forward sides of the hammer heads, and an elastic strip having its opposite ends looped upon the outer end of the pistol barrel and hammer heads respectively.

5. A toy pistol of the character described, 20 comprising a handle grip and barrel including a recessed portion adjacent the rear end thereof, a rotary disk arranged within the upper portion of the recessed portion and including a plurality of oppositely disposed hammer heads upon its periphery and extending upon the upper side of the pistol, a trigger pivotally mounted within the lower portion of the recessed portion and having its upper end engaged in the forward sides 25 of the hammer heads, and an elastic band having its opposite ends extending over the forward end of the barrel and rear sides of the hammer heads respectively.

In testimony whereof, we affix our signatures.

ARCHIE D. PÉPIN.
FRANK P. W. HAACK.
